UNITED STATES PATENT OFFICE

FREDRIC E. DOUGLAS, OF HOPEDALE, MASSACHUSETTS, ASSIGNOR TO DRAPER CORPORATION, OF HOPEDALE, MASSACHUSETTS, A CORPORATION OF MAINE

SHUTTLE SPRING

Application filed February 9, 1932. Serial No. 591,849.

This invention relates to loom shuttles of the type adapted for automatic replenishment of the filling supply and has more particular reference to the means in such a shuttle for holding the filling carrier.

Shuttles of the aforementioned type usually include a pair of opposed bobbin gripping jaws for gripping the butt of the bobbin, and a so-called spring cover, which may be combined with a downwardly and inwardly inclined guide for positioning the incoming bobbin longitudinally of the shuttle during the replenishing operation. Various arrangements of these parts have heretofore been devised. However, insofar as I am advised, such prior devices have been subject to the disadvantages that the spring breakage is excessive and that the parts loosen in the shuttle body.

It is, accordingly, the principal object of my invention to provide a shuttle having a bobbin supporting spring located in a cavity in one end thereof, and a cover member for the spring, wherein the parts are rigidly secured together and wherein the bobbin gripping jaws of the spring are free from any clamping action of the securing means and are consequently less liable to break under the stresses incident to replenishment of the filling supply.

A further object of my invention is to provide a one-piece shuttle spring comprised of opposed bobbin gripping jaws joined at their outer ends by an integral flat portion from the opposite edges of which extend tongues by which the spring may be secured in a shuttle body, one of the tongues also serving to support the jaws and preventing them from mutilating the shuttle body underneath.

Other objects of my invention will, in part, be hereinafter more specifically enumerated or will become apparent as the description proceeds.

Referring to the drawing, which illustrates the preferred embodiment of my invention:

Fig. 1 is a fragmentary plan view of a shuttle embodying my invention:

Fig. 2 is a sectional elevation on a plane

containing the longitudinal axis of the shuttle shown in Fig. 1 and

Figs. 3 and 4 are perspective views of my improved shuttle spring and spring cover, respectively.

As shown more particularly in Figs. 1 and 2, the shuttle, which is of conventional outline, includes a body 1, preferably of wood, having an opening 2 for the reception of a filling carrier, or bobbin, 3. The butt of the bobbin is provided with metal rings 4 adapted to be received in grooves 5 in the contiguous faces of the opposed bobbin gripping jaws 6 of the bobbin supporting spring.

The bobbin supporting spring is, as shown, located in an upwardly opening cavity 7 in one end of the shuttle body, which cavity communicates with opening 2. The cavity is sufficiently large that its walls do not interfere with the free movement of the jaws 6 during the replenishing operation.

The jaws 6 are free at their inner ends, i. e. the ends closest to the opening 2 in the shuttle body, and are joined together at their outer ends by a flat portion 8 extending transversely of the jaws. A flat tongue 9, integral with the portion 8, extends outwardly from the upper edge of said portion and is apertured at 10 for the reception of a bolt or equivalent fastening means 11, the tongue 9 extending beyond the confines of the cavity 7 and overlying the shuttle body. A second flat tongue 12, likewise integral with the portion 8 or junction of the jaws, extends inwardly from the lower edge of such portion, beneath the jaws. As clearly shown in the drawing, the tongue 12 serves as a support, or bearing member, for the jaws 6, preventing the latter from mutilating the ledge 13 of the shuttle body should the impact incident to replenishment of the filling supply tend to spring the jaws downward against said ledge. The tongue 12 overlies the ledge 13 and is apertured as at 14 for the reception of a fastening means such as bolt 15.

As is above indicated, all of the parts of the spring are integrally formed from one piece of metal. While it is not absolutely essential that the spring be so formed such construction is, nevertheless, to be preferred.

Aside from the convenience of being able to stamp the entire spring in one piece, the integral construction also eliminates joints and seams that are liable to break under the severe repeated stresses to which shuttle springs are commonly subjected.

The combined spring cover and bobbin guide is conveniently formed if a single strip of metal having one end 16 in contact with ear 9 and the other end 17 in contact with ear 12, the strip being bent between its ends to form the downwardly and inwardly inclined bobbin guide 18 and the ends being apertured as at 19 and 20 to receive the bolts 11 and 15 respectively.

15 The bolt 11 preferably passes downwardly through the end 16 ear 9 and the body of the shuttle and is threaded into a nut 21 embedded into the lower surface of the shuttle body. The bolt 15 preferably passes upwardly through a spring washer 22, the ledge 13 ear 12 and the end 17 of the cover and is threaded into a nut 23 which, in the present instance, is soldered or otherwise, fixed to the upper face of the end 17.

25 Since the bolts 11 and 15 are spaced apart axially of the shuttle a greater distance than is ordinarily possible they serve to more effectively hold the spring against loosening either from the impact of replenishment or from the stresses imparted by the relatively heavy bobbin when the shuttle is in operation in a loom. Likewise, since the spring is secured in the cavity 7 only by ears 9 and 30 12 the jaws of the spring are not laterally restricted by the clamping action of transverse bolts and, consequently, may separate freely when a fresh bobbin is inserted in the shuttle and the spent one ejected; whereby the 35 stresses in the spring are greatly lessened and the tendency to burst the shuttle body during 40 replenishment is eliminated.

Having fully disclosed the preferred embodiment of my invention, I claim:

45 1. A shuttle including a body having a bobbin supporting spring located in a cavity in one end thereof, said spring including integrally joined bobbin gripping jaws, a 50 tongue extending outwardly from one edge of the junction of the jaws and overlying the shuttle body, a second tongue extending inwardly toward the center of the shuttle from the other edge of the junction of the jaws, and overlying a portion of the shuttle body, and means for securing said tongues to the shuttle body.

55 2. A shuttle including a body having a bobbin supporting spring located in a cavity in one end thereof, said spring including integrally joined bobbin gripping jaws, a tongue extending outwardly from one edge of the junction of the jaws and overlying the shuttle body, a second tongue extending 60 inwardly toward the center of the shuttle

from the other edge of the junction of the jaws, and overlying a portion of the shuttle body, a combined spring cover and bobbin guide having one end in contact with each of the said tongues, and means including 70 bolts each of which passes vertically through one end of the cover, one of said tongues and the shuttle body for securing the cover and spring in the shuttle body.

3. A one piece shuttle spring comprised 75 of opposed bobbin gripping jaws joined by a flat portion extending transversely of the jaws, a flat tongue extending outwardly from the upper edge of the said portion and a jaw supporting tongue extending from the lower 80 edge of said portion inwardly beneath the jaws, said tongues being apertured for the reception of fastening devices for securing the spring in a shuttle body.
